UNITED STATES PATENT OFFICE.

JOHN F. DUSTIN, OF LAWRENCE, MASSACHUSETTS.

APPARATUS FOR APPLYING STOP-MOTION DETECTORS TO WARP-THREADS.

1,072,103.

Specification of Letters Patent.

Patented Sept. 2, 1913.

Application filed August 6, 1912. Serial No. 713,532.

To all whom it may concern:

Be it known that I, JOHN F. DUSTIN, a citizen of the United States, and resident of Lawrence, county of Essex, State of Massachusetts, have invented an Improvement in Apparatus for Applying Stop-Motion Detectors to Warp-Threads, of which the following description, in connection with the accompanying drawing, is a specification, 10 like characters on the drawing representing like parts.

This invention has for its object the production of an apparatus for applying mechanically to a sheet of warp threads the drop bars or detectors by or through which the stop-motion is brought into operation when a warp thread fails or slackens unduly, and I have herein shown a practical embodiment of my invention arranged to 20 apply the detectors to the sheet of warp in a loom.

In the embodiment of my invention herein illustrated I deal with detectors which have a slot-like opening for the reception of the warp thread, each detector being hung upon a single thread, and preferably said detectors are thin, flat strips of sheet metal, each having a thread-receiving slot extended longitudinally thereof and open at its lower 30 end. Above this slot each detector has what may be termed a key-hole aperture, comprising a circular portion and a radial prolongation extending longitudinally of the detector, and the upper end of the latter has 35 a closed, elongated slot adapted for the reception of a transverse support and rotatably movable feeler members, substantially such as shown in United States Patents Nos. 1,043,814 and 1,043,815, granted to me on the 40 12th day of November, 1912.

Heretofore the drop devices or detectors have been applied to the warp by hand, either at the time the latter is drawn into the harnesses, or after the warp has been set up 45 in the loom, and the latter method is the one in most extended use, particularly with the so-called "hairpin" type of detector. This hand application is time consuming and laborious, and my present invention provides 50 a compact, simple form of apparatus whereby the application of the detectors is effected mechanically in a rapid and easy manner, the apparatus being readily removed when the application of the detectors 55 to the sheet of warp has been completed.

The various novel features of my inven-

tion will be fully described in the subjoined specification and particularly pointed out in the following claims.

Figure 1 is a side elevation and part section of an apparatus embodying one practical form of my present invention, on the line 1—1, Fig. 2, showing the apparatus in operative position with relation to the sheet of warp in a loom; Fig. 2 is a part plan view 65 and horizontal section on the line 2—2, Fig. 1, of the apparatus, showing in section portions of the loom sides, and partly broken out; Fig. 3 is a left hand side elevation of the apparatus shown in Fig. 1, the supporting means being omitted; Fig. 4 is a plan and section, on the line 4—4, Fig. 1, looking down, to be referred to; Fig. 5 is an enlarged face view of the detector which has just been discharged from the group of detectors shown in Fig. 1; Fig. 6 is a similar view of the next detector to be discharged and corresponds to the uppermost one at the left, Fig. 1, and also shown in Fig. 3.

In the present embodiment of my invention the operative instrumentalities are mounted on a carriage which is supported above the sheet of warp and movable transversely thereof, the carriage support comprising two parallel rods 1, 1, rigidly connected at their ends by brackets 2, each bracket having a lateral ear 3, Fig. 2, by means of which the bracket is attached temporarily to a part 4 of the loom side, by a suitable bolt 5, the rods constituting a horizontal guideway or track above the sheet of warp and upon which the carriage is movable bodily.

I have shown in Figs. 1, 2 and 4 the warp threads separated into two divisions *w*, *w'* by lease rods *W*, *W'*, and in Figs. 2 and 4 the lateral separation of the warp threads is considerably exaggerated, for clearness in illustration, and the detectors are applied to and hung upon the threads between the lease rods so that adjacent detectors hang from threads in different divisions of the warp, in well-known manner.

Referring to Fig. 1 I have indicated by dotted lines two warp rests *W**, of any suitable construction and of themselves forming no part of my invention. Before describing the apparatus I will refer briefly to the detectors 6, which preferably are thin, flat strips of sheet metal, each having an elongated, closed slot 7 in its upper portion and a longitudinal slot 8 in its lower por-

tion, open at its lower end, see Figs. 5 and 6. Each detector also has, between the said slots, a species of key-hole aperture, comprising a circular portion 9 and a radial extension 10 longitudinal of the detector, but every alternate detector has the extension upturned, while in the intervening detectors said extensions are downturned, for a purpose to be referred to, the upturned extension being shown in Fig. 5, and the downturned extension is shown by dotted lines in Fig. 6. When the detectors are stacked or piled preparatory to being placed in the apparatus they are arranged in alternation, adjacent detectors having the extensions 10 pointing in opposite directions. The stacking can be done readily and cheaply, and in practice preferably a sufficient number of detectors would be stacked to supply a sheet of warp containing a given number of threads. The brackets 2 have rigidly attached to them a non-rotatable, screw-threaded rod 11, between and parallel to the guide rods 1, which latter sustain an upright carriage 12 provided with a foot 13 through which the threaded rod and one of the rods 1 extend loosely, so that the carriage may slide lengthwise thereof.

As shown in Fig. 2 the carriage and its foot are provided with elongated bearing bosses 14, 15 for the guide rods. Vertically aligned bearings 16 on the carriage, above the rod 11, support a shaft 17 having fast upon it at its upper and lower ends bevel gears 18, 19, Fig. 1, said gear 19 meshing with a larger bevel gear 20 in threaded engagement with the rod 11. This gear 20 is in effect a nut, and as it is held from axial movement relatively to the carriage by its location between the foot 13 and a sleeve 21, Fig. 2, loosely surrounding rod 11 and depending from the lower bearing 16, it will be manifest that rotation of the said gear 20 will, by its threaded engagement with the fixed rod 11, cause the carriage 12 and its adjuncts to be moved bodily transversely of the sheet of warp and upon the guideway 1, 1. In Fig. 2 the bodily movement of the carriage is indicated by the arrow. The shaft 17 is a transmitting shaft, and its gear 18 is in mesh with a bevel gear 22 fast on a horizontal actuating shaft 23 rotatable in bearings at 24, 25, the latter being formed in an upright part 26 of the carriage, the shaft being rotated by a suitable handle 27.

Referring to Fig. 1 it will be seen that the part of the shaft in the bearing 25 is enlarged, at 28, and has a still larger head 29 adjacent the face of the carriage part 26, a collar 30 at the opposite face and fixed on the shaft preventing endwise movement thereof. The head 29 and adjacent part 28 of the shaft are longitudinally bored at 31 to receive a detachable cylindrical shaft or

rod 32, held in place by a screw 33, and having a spiral rib 33 around its outer end, shown in Fig. 1 as making one complete turn, the rib and adjacent part of the rod constituting a detector separating and discharging device, and for convenience and brevity termed the separator. The rod 32 is adapted to enter the circular portions 9 of the key-hole apertures of the detectors, and the rib 33 is arranged to traverse the extensions 10 of such apertures, and by rotation to gradually move the detectors longitudinally of the rod, as will be explained, the inner end of the rib being beveled to facilitate its engagement with a detector. The part of said rod or shaft 32 between the head 29 and the rib 33 is adapted to support in upright position a group or series of detectors, as at 6, Fig. 1, arranged face to face and with the extensions 10 in adjacent detectors oppositely extended, as previously referred to. The grouped detectors are prevented from swaying by a forked guide 34 extended horizontally from the upright 26 and coöperating with the depending ends of the detectors which are suspended by the rod 32. Headed plungers 35, slide horizontally in the upright 26 and projected by springs 36, bear against the rearmost one of the group 6 of detectors, and tend to move or feed the group toward the separating device. The inner, beveled end of the rib 33 when engaging the face of the foremost or leading detector of the series acts as a stop for it and for those detectors behind it, but when the said end of the rib comes opposite the extension 10 of the key-hole aperture the feeding action of the plungers 35 will cause said rib to enter such extension and pick up the detector, but it will abut against the face of and stop the next detector until the rod 32 has made a half revolution. Now as the rod is revolved the spiral rib 33 acts upon the endmost detector and moves it longitudinally of the rod, and separates it from its fellows, as shown in Fig. 1.

In Fig. 1 it is supposed that a detector has just been discharged from the separator, that a second one has been separated from the group and is half way along the spiral rib, and that the inner end of the rib is just about to pick off and separate the endmost detector of the group 6. As the rod 32 traverses the circular part 9 of each key-hole aperture, and the rib 33 traverses the offset or extension 10 of such aperture, eccentric to the part 9, the rotation of the separator would tend to turn the detector engaged by the rib 33, but such movement of the detector is prevented by the guide 34, which remains in engagement with a detector until after it is discharged. Consequently the rib 33 acts to move the detector longitudinally from the group of detectors,

along the separator, and finally to discharge it from the outer end of the separator, as will be apparent, whence the discharged detector drops by gravity onto a warp thread, 5 as will now be explained. A strut 37 on the carriage supports a hopper-like directing device or raceway 38, which is slightly wider than the width of a detector, and which has a flared or bell-mouth to receive a dis- 10 charged detector, the raceway decreasing in dimensions at its lower or delivery end, leaving a slit-like outlet opening 39, Fig. 2, through which a detector can slide easily. The outlet 39 is transverse to the warp 15 threads and some little distance above them, so that when a detector, as 6^{xx}, Fig. 1, drops onto a thread the upper end of the detector will be clear of the bottom of said raceway, but the latter will remain in control of the 20 descending detector until the thread has entered the slot or opening 8 in the detector.

From the foregoing it will be seen that by 25 rotating the actuating shaft 23 the detectors will be separated one by one from the group 30 or series of detectors and discharged singly, each discharged detector being guided and directed onto a warp thread as it descends by gravity through the raceway 38, and as the detectors are so discharged the coöperation 35 of the gear 20 and threaded rod 11 will effect a slow step by step motion of the carriage and its adjuncts bodily transversely of and above the sheet of warp. It only remains to position automatically one after 40 another the warp threads so that as each thread is individualized and temporarily separated from its fellows a discharged detector will drop upon it, and I will now describe one means for so individualizing or 45 positioning the warp threads. The lower part of the carriage 12 is provided with a horizontal shelf-like extension 40 cut out around the raceway 38 and extended parallel to the warp threads, said extension having upright 50 tubular bearings 41 for vertically slidable separators, shown as plungers 42, each having a tapered or conical lower end 43, each adapted to pass between and separate laterally two adjacent threads. The side of 55 each bearing 41 has a vertical slot, Fig. 1, through which projects a stud 44 fixed in and extended laterally from the separator, and the two studs enter oppositely inclined cam slots 45 in a plate 46 set on edge and 60 slidable in a guideway 47 in the extension 40, cap-plates 48 retaining the plate 46 in place.

Viewing Fig. 1 it will be seen that the two separators 42 are located between the lease 65 rods W, W' and that the crossing point of the two divisions w, w' of the warp is between said separators, and that the rear separator is down and operative. That is, it has moved down between two warp threads w and w' and has separated them

laterally, individualizing the thread w and positioning it beneath the raceway 38 to receive a detector, as 6^{xx}, delivered therefrom, and at this time the front separator 42 is elevated. Now as the apparatus is actuated 70 the carriage is moved laterally so that the front separator will descend in the position indicated by dotted line 42^x, Fig. 4, to individualize the next thread, which will be one indicated by w'. The reciprocation 75 of the separators is effected by reciprocation of the plate 46 horizontally, the coöperation of the studs 44 and the cam slots 45 causing one separator to rise as the other falls, and vice versa, as will be apparent. To effect 80 the reciprocation of plate 46 (which is built out at 49 around the raceway) I have connected the front end of said plate by a slot-and-pin connection 50, Fig. 1, with the lower end of a lever 51 fulcrumed at 52 on 85 the carriage. At its upper end the lever has a follower roll 53 which travels in the groove 54 of a cam cylinder 55 fast on the actuating shaft 23, the groove being so shaped that for each complete revolution 90 of the shaft the plate 46 will be moved in one direction and back again. That is, as two detectors are discharged from the series 95 or group 6^{xx} at each revolution of the combined separating and discharging device, 100 both thread separators 42 will be moved into and out of operative position with respect to the sheet of warp, in alternation, 105 for every revolution of shaft 23. Thus as the detectors are discharged one by one the carriage is moved bodily across the sheet of warp, and the warp threads are separated, 110 individualized and positioned one by one each to receive a detector as it is delivered from the raceway 38. When the carriage 115 has traversed the full width of the warp the threads thereof will each have been supplied automatically with a detector, and a series 120 of detectors will thus be strung upon the threads, extending across the sheet. Those upon the threads w' will tend to slide forward toward the lease rod W, while those on the threads w will in like manner tend to slide toward the rod W'. The two banks or 125 sets of detectors may be left separate, and a supporting bar can be extended through the slots 7 of each bank, or the lever members and support shown in my patents hereinbefore referred to can be so applied. It will be manifest, however, that it is not material to this invention what particular manipulation of the detectors is adopted, nor the particular character of the coöperating part of the stop-motion, for this invention had for its object the automatic equipment of the warp with drop devices or detectors forming a part of a stop-motion.

I have shown herein one practical embodiment of my invention, but the same may be modified or varied in different 130

tails of construction, arrangement and operation by those skilled in the art without departing from the spirit and scope of my invention as set forth in the claims hereunto
5 annexed.

Having fully described my invention, what I claim as new and desire to secure by Letters Patent is:

1. In apparatus of the class described, 10 means to support in upright position a group of detectors above the sheet of warp; means to separate and discharge the detectors one by one from the group; a device to direct the separated and discharged detectors onto the warp threads, each detector having a thread-receiving opening provided with an unobstructed entrance for the passage of the thread, and means to position one after another of the warp threads for
20 the reception of a detector.

2. In apparatus of the class described, a support for a group of detectors each having a thread-receiving opening provided with an entrance for the thread, means to 25 separate and discharge the detectors one by one from the group; a device to direct the separated and discharged detectors onto the warp threads in a sheet of warp, and means to position the warp threads one by one for
30 the reception of a detector, the positioned thread passing through the entrance into the opening in the detector when the latter is directed onto such thread.

3. In apparatus of the class described, 35 means to support above the warp a group of detectors placed face to face in upright position, each detector having a thread-receiving opening; means to separate the detectors from the group and discharge them
40 one by one; a device to receive the discharged detectors and present them in upright position to the warp threads, to hang thereupon, and means to individualize successively the warp threads of a sheet of
45 warp and position the individualized threads for coöperation with a detector directed thereto.

4. In apparatus of the class described, 50 means to support above the warp a group of detectors placed face to face in upright position, each detector having a thread-receiving opening; means to separate the detectors from the group and discharge them one by one; an upright raceway having a
55 flaring mouth, to receive the discharged detectors and direct them in upright position onto the warp threads, and means to coöperate with one thread after another in a sheet of warp and position the thread for
60 the reception of a detector delivered by the raceway.

5. In apparatus of the class described, 65 means to support above the warp a group of detectors each having a downwardly open thread-receiving slot; means to discharge

the detectors one by one from the group; a device to direct a discharged detector in upright position, onto a warp thread, the thread entering the slot in the detector, and means acting upon one after another of the threads in the sheet of warp to position the threads singly for the reception of a detector.

6. In apparatus of the class described, 70 means to temporarily and laterally separate from its fellows one after another of the threads of a sheet of warp; a device to direct a detector onto the separated thread, and means to deliver a single detector to said device each time a warp thread is positioned for the reception of a detector, each detector having an open slot to receive the thread.

7. In apparatus of the class described, 75 means to separate temporarily from its fellows one after another of the threads of a sheet of warp; a raceway to direct a detector onto the separated warp thread and maintain the detector in upright position as it is directed to the thread; means to deliver detectors one by one to the raceway, 80 each detector having an open thread-receiving slot; a carriage on which the threads separating and detector-delivering means are mounted, and an instrumentality to 85 move said carriage step by step transversely of the sheet of warp.

8. In apparatus of the class described, 90 means to support in upright position above the sheet of warp a group of detectors placed face to face and each having a thread-receiving slot; a directing device below said means, to receive and direct detectors discharged from the group, and automatic means to engage the endmost detector of the 95 group, separate it therefrom, and discharge the separated detector into said directing device, whereby the detectors are separated one by one from the group and discharged therefrom.

9. In apparatus of the class described, 100 means to support in upright position face to face a group of detectors each having a downwardly open slot, and a key-hole aperture, the extensions of the apertures in adjacent detectors extending in opposite directions, a rotatable, spiral separator to enter the said apertures and separate the detectors one by one from the group, the separator moving one detector away from the 105 group while holding the next detector, and the group, from such movement, and means to direct detectors to the threads of a sheet of warp as they are discharged one by one by the separator, each thread entering the 110 open slot of a detector as the latter is directed to the thread.

10. In apparatus of the class described, 115 warp separating means; a device to direct detectors to the separated warp, each de- 120

5 tector having a key-hole aperture and a thread-receiving, open slot; means to support a group of upright detectors, comprising a rotatable shaft to traverse the apertures and support the detectors, a guide for the lower ends thereof, and a follower to feed the group along the shaft; and means mounted on the outer end of said shaft to engage one after another of the detectors, 10 separate them from the group, and discharge them singly into the said directing device.

11. In apparatus of the class described, means to support a group of detectors each 15 having an open thread-receiving slot; means to separate and discharge the detectors one by one from the group; a device to direct the discharged detectors onto the threads of a sheet of warp; means to individualize and 20 position the threads one after another for the reception of the detectors, said means comprising a reciprocating tapered spreader to enter between and separate laterally adjacent threads, and an instrumentality to 25 move said spreader step by step, across the sheet of warp.

12. In apparatus of the class described, a carriage, means to move it step by step transversely of a sheet of warp; a pair of 30 vertically and alternately reciprocating, tapered spreaders mounted on the carriage and adapted at each descent to separate laterally a warp thread from its fellows, whereby one after another of the threads are 35 acted upon as the carriage is moved transversely of the warp, and means to direct detectors onto the separated threads, each detector having a slot to receive the thread onto which it is directed.

40 13. In apparatus of the class described, a carriage, a guideway therefor located above and transverse to a sheet of warp; means on the carriage to separate one after another of the warp threads and position 45 the same for the reception of a detector; means on the carriage to separate detectors one by one from a group of detectors, the separated detectors descending by gravity onto the warp threads, each detector having 50 an open thread-receiving slot; means to move the carriage step by step along its guideway; an actuating member, and operating connections between it and the several means before-mentioned.

55 14. In apparatus of the class described, a carriage, a guideway for and to support the carriage above a sheet of warp, the carriage movable lengthwise of said guideway; actuating means to effect such movement 60 step by step; means on the carriage having provision for supporting in upright position a group of detectors face to face and each having a thread-receiving opening; means operatively connected with said actuating 65 means to separate and discharge periodically

a detector from the group, the discharged detector descending by gravity to the sheet of warp; and means on the carriage and operating automatically to present one thread after another in position to receive a discharged detector. 70

15. In apparatus of the class described, means movable bodily adjacent to and transversely of the sheet of warp to position the threads one by one for the reception of detectors each having an open thread-receiving slot, an instrumentality to deliver detectors one by one to the threads as they are positioned, said instrumentality being movable bodily in unison with the thread-positioning means, and mechanism to effect step by step bodily movement of said means and the detector-delivering instrumentality. 75

16. In apparatus of the class described, means adjacent the sheet of warp to position the threads thereof one by one for the reception of detectors having open thread-receiving slots, an instrumentality to deliver detectors one by one and move them on to the threads as they are positioned, such 80 thread passing into the open slot of the detector as the latter is delivered and means to effect step by step relative lateral movement of the sheet of warp and said instrumentality and the warp-positioning means. 85

17. In apparatus of the class described, a support for a series of detectors placed face to face and each having a thread-receiving opening; a separator to engage the leading detector of the series and discharge 90 it therefrom, a device through which the discharged detector passes by gravity to thread-engaging position, and means to position the warp threads one by one below said device to receive the detector as it emerges therefrom, combined with mechanism to effect simultaneous bodily movement of said several means step by step transversely of the 95 warp. 100

18. In apparatus of the class described, a guideway adapted for attachment to the sides of a loom above the warp, a carriage movable upon and longitudinally of the guideway, warp separating means on the carriage, to position the threads one by one 110 for the reception of a detector; a support for a series of detectors placed face to face and each having an open warp-receiving slot, said support being mounted on the carriage; a separator to engage the leading detector 115 of the series and discharge it; a raceway connected with the carriage and through which a discharged detector passes to engage and hang upon a warp thread; means to feed the series toward the separator, and 120 mechanism to effect gradual movement of the carriage along the guideway, to thereby place the detectors on one after another of the threads of the warp sheet. 125

19. In apparatus of the class described, 130

means to support in upright position a series of open-slotted detectors placed face to face and each having a key-hole aperture, the extensions of adjacent detectors projecting 5 in opposite directions; a rotatable, spiral separator to enter the apertures of the detectors and separate them one by one from the series, rotation of the separator effecting movement longitudinally thereof of the separated detector, to discharge the same; a 10 directing device through which the discharged detector passes by gravity with its

open slot downturned, and means to position one by one the threads of a sheet of warp for the entrance of the positioned thread 15 into the open slot of a detector passing from the directing device.

In testimony whereof, I have signed my name to this specification, in the presence of two subscribing witnesses.

JOHN F. DUSTIN.
